COMPRESSION RELIEF DEVICE FOR
STARTING ENGINES

Cirilo C. Castillo, Los Angeles, Calif.

Application April 22, 1947, Serial No. 743,022

6 Claims. (Cl. 123—182)

1

This invention relates to a compression relief device for starting an engine.

The general object of the invention is to provide an improved apparatus for effecting prompt starting of a high compression internal combustion engine such as of the Diesel type.

A more specific object of the invention is to provide a novel means for actuating the compression reducing member of a Diesel engine to low compression position and thereafter causing actuation of the starter mechanism.

A further object of the invention is to provide a novel, manually actuated, valve controlled, compressed air operated starter for Diesel engines.

Other objects and advantages of my invention will be apparent from the following description, taken in connection with the accompanying drawings, wherein

Fig. 1 is a diagrammatic view, with parts in section showing an automotive vehicle with my improved starter applied thereto;

Fig. 2 is a section taken on line 2—2, Fig. 1;

Fig. 3 is a section taken on line 3—3, Fig. 1;

Fig. 4 is a view similar to Fig. 3, showing parts in another position;

Fig. 5 is a section taken on line 5—5, Fig. 3;

Fig. 6 is a fragmentary section taken on line 6—6, Fig. 3;

Fig. 7 is a fragmentary section taken on line 1—7, Fig. 5;

Fig. 8 is an enlarged elevation with parts in section showing the starter operating mechanism;

Fig. 9 is a fragmentary section taken on line 9—9, Fig. 4;

Fig. 10 is a sectional view taken on line 10, Fig. 2, and

Fig. 11 is a section through the engine flywheel housing showing the connection of the engine starter to the engine shaft.

Referring to the drawing by reference characters, I have shown my invention as embodied in a starting apparatus which is indicated generally at 10. As shown, the apparatus is mounted on an automotive vehicle 11 which is driven by a Diesel engine 12.

The engine includes a flywheel 12a, having a housing 12b thereabouts. The engine includes a shaft 12c, which is connected to the flywheel. The flywheel includes teeth 12d, which mesh with teeth 12e on a starter gear 12f. The starter gear 12f is mounted on a shaft 12g, which is driven by a starting motor. Mechanism of this type for

2

turning over the motor is old and forms no part of the present invention.

Diesel engines operate under a high compression and in order to permit the starting motor to operate, it is necessary that this compression be decreased while the starting motor is building up speed in the engine. To permit this decrease of compression in the cylinders, Diesel engines are usually provided with means such as an arm 13 mounted on a shaft 14 and the construction is such that when the arm is rocked from a full line position in Fig. 2 to a broken line position in this figure the compression will be reduced. The mechanism of this type for reducing compression is old and forms no part of the present invention.

Referring again to the drawing, I have shown the arm 13 as engaged by one end 15 of a spring 16. The other end 17 of the spring is shown as attached to a boss 18 on the engine 12 so that the compression is normally fully maintained.

In order to first break the compression and cause the starter to be operated, I provide a cylinder 19 which has a forwardly projecting arm 20 which has a slot 21. The arm is pivotally attached to the boss 18 by a threaded shaft 22. The cylinder 19 receives a piston 23 which has a piston rod 24 passing through a head 25 on the cylinder. The piston rod 24 includes an end fitting 26 which is secured by a pin 27 to the free end of the arm 13.

The forward end of the cylinder 19 is provided with a fitting 28 which is connected to a flexible tube 29 through which compressed air may be delivered to the cylinder. The cylinder also includes another fitting 30 which is connected to a flexible tube 31 which leads to the starter. Thus when compressed air passes through the pipe 29 to the cylinder it will operate the piston 23 causing the latter to move the arm 13 to the broken line position in Fig. 2 and during its motion after the arm 13 has been rocked to compression breaking position the piston will clear the fitting 30 thus permitting compressed air in the cylinder to pass through the pipe 34 to the starter. The starter includes an operating member 32 which is conventional and which when pushed will cause the starting motor to turn over the engine crank shaft.

In my construction, as shown, I mount a sleeve 33 about the starter button. The cylinder includes opposed slots 34 through which pins 35 move. The pins 35 are mounted in a sliding inner cylinder 36 which has a closed end 37. The end 37 includes a bleed aperture 37'. The inner

cylinder 36 includes a fitting 38 at one side and a slot 39 in the sleeve 33 permits movement of the fitting 38 and the cylinder 36. The tube 31 is preferably flexible and is connected to the fitting 38 so that compressed air from the tube 31 may pass to the interior of the sliding cylinder 36 to cause inward movement of a piston 40. The piston 40 engages the starter member 32 so that when compressed air passes through tube 31 the piston 40 will cause an inward movement of the starter member 32 to operate the starter. The conventional starter stem 32 is normally spring pressed so that the piston 40 is urged to the position shown in Fig. 6.

To permit operation of the starter in the absence of a supply of compressed air, I may mount a plunger 41 on the foot board 42 of the vehicle. The plunger is normally urged to the position shown in Fig. 6 by a spring 43. A head 44 of the plunger 41 engages the head 37 of the cylinder 36 so that when a button 45 on the stem 41 is depressed the cylinder 36 will move inwardly and the head 37 will engage the piston 40 and will move the latter, causing the starter member 32 to be depressed.

It will be understood that the plunger 41 and associated parts provided for effecting the starting operation are of an emergency nature and would only be operated on rare occasions when the supply of compressed air is exhausted.

In order to supply compressed air to the pipe 29, I provide a pipe 50 which is connected by a fitting 51 to a compressed air reservoir 52 which is provided with compressed air from any suitable source. The pipe 50 is connected by a fitting 53 in a control valve base 54. The fitting 53 communicates with a chamber 55 in the base 54. The chamber 55 in turn communicates with a check valve 56 which includes a projecting valve ball 57 which is normally seated as by a spring 57'. The valve ball 57 prevents normal passage of air through the pipe 50. The valve base 54 has a cavity 58 in which a control valve member 59 rotates. The valve 59 includes a stem 60 which passes through a hole 61 in a closure 62. The closure is held in place as by bolts 63.

The lower face of the valve 59 includes a depending boss 64 which may have a cam end 65. The boss 64 extends peripherally about the valve head 59 so that when the valve head is turned (in the act of starting the engine, as will be later described), the cam 65 will engage the valve ball 57 to open the valve 56 and allow compressed air to pass from the pipe 50 to the chamber 58.

The closure 62 includes a radially drilled hole 70 which communicates with a hole 71 which latter extends to the inner face of the closure 62 to form a vent opening. The closure 62 also includes a fitting 72 which communicates with the pipe 29 previously described. The stem 60 includes an operating handle 73 by means of which the valve 59 may be turned.

The valve 59 includes a chordal bore 75 which at one end communicates with an upwardly opening hole 76 and at the other end communicates with a second upwardly opening hole 77. Pins 78 limit the movement of the handle 73. When the handle 73 is in the position shown in Fig. 3 the holes 76 and 77 are both closed. When the handle 73 is in the position shown in Fig. 4, the hole 77 communicates with the hole 76 and through the hole 70 to the atmosphere but at the same time the hole 76 communicates with a hole 78 which in turn communicates with a radial

hole 79 in the closure 62. The hole 79 communicates with the fitting 29.

When the parts are in the position shown in Fig. 3, the hole 79 communicates with a hole 80 in the closure 62 and the hole 80 communicates with a hole 81 in the valve 59. The hole 81 communicates with the chamber 58 so that in the position of Fig. 3 compressed air passes through the pipe 50, the valve 57, which is then open to the chamber 58, through hole 81, hole 79 and to pipe 29 to actuate the piston 23 to thereby rock the arm 13 and thus break the compression. As soon as the piston 23 clears the fitting 30 compressed air passes through the tube 31 and fitting 38 to the cylinder 36, thus causing the piston 40 to move the starter member 32 to thus actuate the starter while the compression is broken. As soon as the starter is running the handle 73 is moved to the position shown in Fig. 4. In this position the pipe 29 communicates with the aperture 78 and through the holes 76, bore 75, hole 77, hole 71 and hole 70, to the atmosphere. This bleeds the cylinder 19 so that the spring 16 moves the compression controlling arm 13 to full compression position and the engine operates independent of the starter. Air in the cylinder 36 gradually bleeds therefrom through the holes 37'.

In the absence of a supply of compressed air, the arm 13 may be rocked manually to the broken line position shown in Fig. 2 and thereafter the button 45 may be depressed to push the cylinder 36 inwardly and thereby actuate the starter.

From the foregoing description it will be apparent that I have invented a novel starting device which is simple in construction and is reliable in operation.

Having thus described my invention, I claim:

1. In a starting device for an internal combustion engine which includes a shiftable compression releasing arm and a movable starter operating member, a cylinder, means adapted to support the cylinder on an engine, a piston in the cylinder, means adapted to connect the piston to a compression releasing arm, a source of compressed air, a control valve, conduit means connecting the source of compressed air to the control valve, means connecting said control valve to said cylinder, said control valve when in "on" position permitting flow from the source to the cylinder, means to bleed the cylinder to the atmosphere when the control valve is in "off" position, a second cylinder adapted to be disposed adjacent to a starter operating member, a second piston in the second cylinder, said second piston being adapted to actuate a starter operating member, conduit means to supply fluid to the second cylinder after the first piston has started its movement, and means adapted to normally urge the compression releasing arm to full compressed position.

2. In a starting device for an internal combustion engine which includes a shiftable compression releasing arm and a movable starter operating member, a cylinder, means adapted to support the cylinder on an engine, a piston in the cylinder, means adapted to connect the piston to a compression releasing arm, a source of compressed air, a control valve, conduit means connecting the source of compressed air to the control valve, said conduit means including a check valve normally preventing the flow from the source of compressed air to the control valve, means operable when the control valve is moved from "off" position to release the check valve to permit compressed air to pass to said control

valve, means connecting said control valve to said cylinder, said control valve when in "on" position permitting flow from the source to the cylinder, means to bleed the cylinder to the atmosphere when the control valve is in "off" position, a second cylinder adapted to be disposed adjacent to a starter operating member, a second piston in the second cylinder, said second piston being adapted to engage a starter operating member, conduit means to supply fluid to the second cylinder after the first piston has started its movement, and means adapted to normally urge the compression releasing arm to full compressed position.

3. In a starting device for an internal combustion engine which includes a shiftable compression releasing arm and a movable starter operating member, a cylinder, means adapted to support the cylinder on an engine, a piston in the cylinder, means adapted to connect the piston to the compression releasing arm, a source of compressed air, a control valve, conduit means connecting the source of compressed air to the control valve, means to bleed the cylinder to the atmosphere when the control valve is in "off" position, a sleeve cylinder adapted to be disposed adjacent to a starter operating member, an inner cylinder in said sleeve, means to limit the movement of the inner cylinder in the sleeve, a piston in the sleeve, said piston being adapted to engage a starter operating member, manual means for moving said sleeve to actuate the starter, conduit means to supply fluid to the inner cylinder, and means to connect the last mentioned conduit means to the first cylinder at a location to permit passage of compressed air to the last mentioned conduit when the first mentioned piston approaches the outer limit of its movement.

4. In a starting device for an internal combustion engine which includes a shiftable compression releasing arm and a movable starter operating member, a cylinder, means adapted to support the cylinder on an engine, a piston in the cylinder, means adapted to connect the piston to the compression releasing arm, a source of compressed air, a control valve, conduit means connecting the source of compressed air to the control valve, said conduit means including a check valve normally preventing flow from the source of compressed air to the control valve, means operable when the control valve is moved from "off" position to release said check valve to permit compressed air to pass to said control valve, means connecting said control valve to said cylinder, said control valve when in "on" position permitting flow from the source to the cylinder, means to bleed the cylinder to the atmosphere when the control valve is in the "off" position, a second cylinder adapted to be disposed adjacent to a starter operating member, a second piston in the second cylinder, said second piston being adapted to engage a starter operating member, conduit means to supply fluid to the second cylinder, means to connect the last mentioned conduit means to the first cylinder at a location to permit passage of compressed air to the last mentioned conduit when the first mentioned piston approaches the outer limit of its movement, and means adapted to normally urge the compression releasing arm to full compressed position.

5. In a starting device for an internal combustion engine which includes a shiftable compression releasing arm and a movable starter operating member, a cylinder, means adapted to support the cylinder on an engine, a piston in

the cylinder, means adapted to connect the piston to a compression releasing arm, a source of compressed air, a control valve, conduit means connecting the source of compressed air to the control valve, said conduit means including a check valve normally preventing flow from the source of compressed air to the control valve, means operable when the control valve is moved from "off" position to release said check valve to permit compressed air to pass to said control valve, means connecting said control valve to said cylinder, said control valve when in "on" position permitting flow from the source to the cylinder, means to bleed the cylinder to the atmosphere when the control valve is in "off" position, a sleeve adapted to be disposed adjacent to a starter operating member, a second cylinder in said sleeve, means to limit the movement of the second cylinder in the sleeve, a second piston in the second cylinder, said second piston being adapted to engage a starter operating member, manual means for moving said second cylinder to actuate a starter, conduit means to supply fluid to the second cylinder, means to connect the last mentioned conduit means to the first cylinder at a location to permit passage of compressed air to the last mentioned conduit when the first mentioned piston approaches the outer limit of its movement, and means adapted to normally urge the compression releasing arm to full compressed position.

6. In a starting device for an internal combustion engine which includes a shiftable compression releasing arm and a movable starter operating member, a cylinder, means adapted to support the cylinder on an engine, a piston in the cylinder, means adapted to connect the piston to a compression releasing arm, a source of compressed air, a control valve including a valve chamber, conduit means connecting the source of compressed air to the chamber, said conduit means including a check valve, a valve member rotatable to "on" and "off" positions and disposed in said chamber, means carried by the valve member and operable when the valve member is moved from "off" position to release said check valve to permit compressed air to enter said chamber, a closure for said chamber, said closure having a conduit therein, means connecting said conduit to one end of said cylinder, said valve member having a conduit therethrough, said conduit communicating when the valve member is in "on" position with said chamber and said last mentioned conduit, said closure having a second conduit, said second conduit communicating with the atmosphere at one end, said valve member having a conduit communicating with the other end of said second conduit when the valve member is in "off" position, said closure having an exhaust conduit communicating with said first valve member conduit, said closure exhaust conduit communicating with said first valve member conduit when the valve member is in "off" position to bleed the cylinder, a sleeve adapted to be disposed adjacent to a starter operating member, a second cylinder in said sleeve, means to limit the movement of the second cylinder in the sleeve, a second piston in the second cylinder, said second piston being adapted to engage a starter operating member, manual means for moving said second cylinder to actuate a starter operating member, conduit means to supply fluid to the cylinder, means to connect the last mentioned conduit means to the first cylinder at a location to permit passage of com-

pressed air to the last mentioned conduit when the first mentioned piston approaches the outer limit of its movement, and means adapted to normally urge the compression releasing arm to full compression position.
